UNITED STATES PATENT OFFICE.

MURDOCK McNEIL, OF EAST CAMBRIDGE, ASSIGNOR OF ONE-FOURTH TO
RICHARD S. SMITH, OF BOSTON, MASSACHUSETTS.

STEAM-PRESSURE GAGE.

SPECIFICATION forming part of Letters Patent No. 278,164, dated May 22, 1883.

Application filed October 25, 1882. (No model.)

To all whom it may concern:

Be it known that I, MURDOCK McNEIL, of East Cambridge, in the county of Middlesex, of the State of Massachusetts, have invented 5 a new and useful Improvement in Steam-Pressure Gages; and I do hereby declare the same to be described in the following specification and represented in the accompanying drawings, of which—

10 Figure 1 is a front view, and Fig. 2 a vertical and longitudinal section, of the portion of a pressure-gage containing my invention, the nature of which is defined in the claim herein-after presented.

15 The improvement is to prevent the helical or volute spring of the gage from becoming choked by the elastic septum or disk, against which the steam presses or directly acts, such septum heretofore generally resting immediately against the convex side of the volute or helical spring.

20 In Fig. 2 of the drawings, A denotes the arched helical or volute spring, and B its sustaining-cup, provided with a cap or cover, C, 25 which is screwed upon such cup, and with it constitutes an inclosing-case for parts to be described. The spindle D, that extends through the spring, has fixed upon it concentrically, and with respect to the spring in manner as shown, 30 a disk, E, provided with a cylindrical shoulder, F, extending from it concentrically. Surrounding the disk is an annular cover, G, having at its middle a circular opening, a, larger in diameter and to receive the shoulder F. 35 Resting against the cover G, and held firmly to such and the shoulder F by the cover C, is the elastic disk or septum I, of vulcanized in-

dia-rubber. There is to the cover C an induct, b, for admission of the steam into the inclosing-case and to the septum, and there is to the cup B a hollow neck, c, which connects it with the dial-case of the gage, the spindle D being suitably adapted to the mechanism for working the index-hand of such gage. The cover G, at its edge, fits into an annular groove, y, in 45 the case and against a packing, x, arranged in such grooves, such cover being forced closely against the said packing by the cover C when screwed on the cup B.

40 From the above it will be seen that when 50 the steam presses upon the elastic septum a portion of such septum will be pressed into the space immediately around the shoulder F and upon such shoulder, and will crowd the disk E against the spring at the central convolution or part of the latter. By means of the said disk E and the perforated cover G, the spring becomes completely insulated from the elastic septum, which, not resting against the spring, cannot be forced between its coils 55 60 so as to choke them and become injured by them.

I claim—

65 In combination with the pressure-gage, arched helical spring, and its spindle, and their elastic septum, arranged in an inclosing-case, as set forth, the disk and its shoulder applied to the said spindle, and the perforated cap arranged in such case and with the spindle and septum, substantially as set forth.

MURDOCK McNEIL.
